SPECIFICATION forming part of Design No. 23,657, dated September 25, 1894.

Application filed December 30, 1893. Serial No. 495,259. Term of patent 3½ years.

To all whom it may concern:

Be it known that I, HENRY J. HEINZ, of Pittsburgh, in the county of Allegheny and State of Pennsylvania, have invented a new and original Design for Advertising-Checks, of which the following is a full, clear, and exact description, reference being had to the accompanying drawing, which shows in plan view an advertising-check embodying my design.

10 sign.

My design consists in an advertising check having substantially the form and pattern hereinafter described and shown in the drawing.

15 In the drawing, 2 represents the advertising check, 3 a transverse oblong opening formed

near one end thereof, and 4 a pattern, whose outline is substantially that of a key-stone, delineated on the surface of the check.

The leading and characteristic feature of 20 my design is the outline of the check, having thereon the keystone pattern and above the same the transverse oblong opening 3.

I claim—

The design for an advertising check substantially as herein shown and described.

In testimony whereof I have hereunto set my hand.
